UNITED STATES PATENT OFFICE.

CARL V. J. CHRISTENSEN, OF ATTLEBORO, MASSACHUSETTS.

AUTOMATIC-LOCKING COLLAR.

No. 836,303.

Specification of Letters Patent.

Patented Nov. 20, 1906.

Application filed April 26, 1906. Serial No. 313,828.

To all whom it may concern:

Be it known that I, CARL V. J. CHRISTENSEN, a citizen of the United States, residing at the town of Attleboro, in the county of Bristol and State of Massachusetts, have invented certain new and useful Improvements in Automatic-Locking Collars, of which the following is a specification, reference being had therein to the accompanying drawings.

- This invention relates to self-locking collars, and has for its object to provide a collar that may be adjusted either up or down on a spindle and one that will lock automatically in any position on said spindle against a further movement in one direction, or, if desired, the collar may be fixed and the spindle may be moved up and down at will through said collar and be locked automatically against a further movement in one direction.
- The device is constructed of a shell or collar having located within it one or more plates similar in construction to a washer, said plates being arranged to automatically cramp or bind and grip the spindle when the same is trying to pass through in one direction.

A feature of this invention is that the hole in said washer or plate through which the spindle passes is made polygonal in form, preferably hexagonal, so as to concentrate the bite of the grip-plate into four distinct points, two in back and two in front, instead of distributing the said bite over a greater contact-surface, as would be the case if the hole in the plate were round. This form of hole that has straight sides insures a bite that will not slip, even when applied to a spindle having a hardened surface and will sustain a heavy load with safety.

The invention is fully set forth in this specification and more particularly pointed out in the appended claims.

In the accompanying drawings, Figure 1 is a view showing the collar in section and the grip-plate in position to bind the spindle. Fig. 2 is the same as Fig. 1 with the exception that there are two grip-plates for binding the spindle instead of one. Fig. 3 represents a plan view of the grip-plate as illustrated in Fig. 1, showing it in position to present the four distinct points in contact with the spindle. Fig. 4 is an edge view of said grip-plate, showing the actuating end or handle. Fig. 5 represents a plan view of the grip-plate, showing the contact-finger raised out of the stock, such as that illustrated in

the lower plate in Fig. 3. Fig. 6 is an edge view of said plate in detail, showing the contact-finger. Fig. 7 is a sectional plan view of the shell or collar on line 7 7 of Fig. 1. Fig. 6 60 8 represents a support in which the shelf of a display-stand rests upon the collar, which automatically locks itself to the standard. Fig. 9 represents another style of display-stand in which the weight is applied to the 65 spindle instead of the collar, giving the reverse action to the grip-plates to that illustrated in Fig. 8. Fig. 10 is another form of display-stand, which has my automatic locking collar connected to the spindle, which 70 acts similar to that illustrated in Fig. 8.

Referring to the drawings, at 1 is the spindle, which may be used on a bracket, extension-stand, or the like, as shown in Figs. 8, 9, and 10, or it may serve in any other capacity 75 in connection with my device where the same may be conveniently applied. At 2 is the shell or collar, that may be constructed in any convenient way. When it is desired to have the spindle adjustable through said collar, the latter is preferably supported on a tubular standard 3, such as that best illustrated in Fig. 9. Another construction is illustrated in Fig. 8, where the collar is adjustable on the spindle. 85

In order to form a convenient rest for one edge of the grip-plate, a little tongue 4 is formed by pressing in a narrow piece of the side or wall of the shell, the wall directly opposite this tongue being slotted at 5 to admit 90 of a movement of the actuating-handle of the said grip-plate. When it is desired to use the shell on a tube, it may be screwed onto the same, as illustrated at 6 in Fig. 1.

A cap or cover 7 may be fitted into the upper edge of the collar to inclose the same and also to form an upper bearing on the spindle or shaft. This cap may be permanently retained in its position by having the upper edge of the collar turned over the same, if desired, as illustrated in Fig. 2, or said cap may be removably fitted into the upper edge of the collar, as illustrated in Fig. 1, to allow the same to be readily removed for inspection or repairs of the operating parts. This latter 100 construction is found in practice to be very convenient and that for ordinary service the said cap may be sprung into the thin metal collar and held firmly in position without the necessity of using further retaining means. 105

At 8 is the grip-plate, preferably made of sheet-steel stamped out in a substantially

circular form, as shown in Fig. 3, with a narrow neck or projection 9 extending from one side thereof and turned up at its outer end at 10, with the outer face of the turned-up portion knurled or roughened to be more readily engaged by the thumb or finger to lift it. Through this plate is formed a hole, preferably hexagonal in shape, the essential feature being to form an angular hole that will present a plurality of contact-points to the spindle when tipped up on an angle, as shown in Fig. 1.

As illustrated in Fig. 3, a hexagonal hole presents four contact-points 13 13 and 14 14, two in back and two in front of the spindle, which, as determined by experiment and practical experience, gives the best possible results to the gripping-plate. This plate, as shown in Fig. 1, fits loosely in the shell 2 and has its extending portion or handle 10 projecting out through the slot 5 in the wall of said shell, the opposite side of the plate being supported on the little tongue 4. At 11 is a small coil-spring to normally hold said plate down in contact with the spindle, one end of said spring being turned down through the hole 12 to hold it in place.

Figs. 2, 5, and 6 illustrate another construction of my device, in which two gripping-plates 15 and 16 are shown instead of one, as in Fig. 1. Each of these plates may be supported from the back edges on separate tongue 4 4; but both may be operated to release the spindle by the upward movement of the lower plate. As is illustrated in these figures, this plate is provided with a horn or finger 17, which will engage and raise the upper plate when the lower plate is raised. At 18 is a coil-spring pressing down on the upper plate, and at 19 is shown a spring drawing down the lower plate.

Any number of binding-plates may be employed in my device, according to the weight desired to be held.

To operate the device in the form illustrated in Figs. 1 and 9, where the spindle or shaft is adjustable and supports the weight, the collar is preferably supported on a tubular standard and may be connected to said standard in any suitable manner. The gripping-plate 8 is set into the collar in which it fits loosely, with one edge resting on the tongue 4 and the actuating-handle 10 on its opposite side projecting out through the wall of the collar. The hole in this plate is made with a plurality of sides and somewhat larger than the spindle that passes through it. On account of supporting one edge only of this gripping-plate on the wall of the collar the opposite side naturally falls until the edges of the stock around the hole engages both the back and front of the spindle. Any weight or force exerted by this spindle to press downward naturally tends on account of the inclined position of the plate to cramp or

bind the spindle to prevent it from further downward movement, the principle being that the greater the weight on the spindle the more the grip-plates will cramp and bind the same.

To release the spindle or shaft, it is only necessary to raise the handle 10 by a slight pressure of the thumb or finger, and said spindle may then be moved freely up or down; but upon releasing the handle 10 the spring 11 acts on the plate and throws it quickly down into the sliding position to bite the spindle and hold it firmly from further downward movement, it being always free, however, to be moved in the opposite direction. When it is desired to use the collar on a fixed spindle to support a shelf or plate, as illustrated in Figs. 8 and 10, the grip-plate located therein is held in an inverted position, the spring being beneath it to hold it up against the tongue 4, its action being directly opposite to that illustrated in Figs. 1 and 9. When it is desired to move the collar downward on the spindle, the thumb or finger presses the handle of the said grip-plate downward, which naturally releases the gripping or binding effect on the spindle and the collar may be freely moved in either direction.

This device is extremely simple and practical in its construction and efficient in its operation. On account of the angular shape of the hole a plurality of distinct gripping and biting points are presented simultaneously to the spindle, effectually binding the same and preventing a further downward movement against a heavy weight. Any number of gripping-plates may be used in the collar and, as illustrated in Fig. 3, all of said plates may be actuated with one operating-handle.

Having thus described my invention, what I claim as new, and desire to secure by Letters Patent, is—

1. A device of the character described comprising a closed shell or casing the wall of which is cut to form a tongue, said tongue being bent inwardly, a gripping-plate located in said casing and provided with a finger-piece, a standard passing through said plate and said casing, means for holding said plate in engagement with the end of said tongue, whereby said plate is normally in position to grip said standard, and a removable cap fitting within said casing and forming a bearing for said shaft.

2. A device of the character described comprising a closed shell or casing the wall of which is cut to form a tongue, said tongue being bent inwardly, said shell being also provided with a reduced tubular portion, a gripping-plate located in said casing and provided with a finger-piece, said plate being provided with a polygonal opening, a standard passing through said casing and also

through the opening in said plate, means for holding said plate in engagement with the end of said tongue, whereby said plate is normally in position to grip said standard, and a 5 removable cap fitting within the end of said casing, said cap being provided with a flange forming a bearing for said shaft.

3. In a locking collar, a shell, a plurality of grip-plates mounted in said shell, a standard extending through said shell and plates, means whereby said plates are held in an inclined position to each grip said standard independently and automatically to prevent an endwise movement of the same in one direction, and means carried by one plate to simultaneously move the other plate when the first-mentioned plate is moved to unlocking position.

4. In a locking collar, a shell, a plurality of grip-plates mounted in said shell, a standard extending through said shell and plates, each of said plates being provided with a polygonal-shaped hole and arranged to present a plurality of distinct gripping-points to said standard, means whereby said plates are held in an inclined position to each grip said standard independently and automatically to prevent an endwise movement of the same in one direction, and means whereby 25 all of the said plates may be moved to unlocking position by the movement of one plate.

5. A device of the character described

comprising a shell or casing, a plurality of gripping-plates located in said casing, a 35 standard passing through said plates and said casing, means for holding said plates in position to grip said standard, and means integral with one of said plates and projecting from said casing, whereby the same may be 40 moved, and means for simultaneously releasing all of said plates from their gripping positions by movement of the first-mentioned plate.

6. A device of the character described 45 comprising a shell or casing, the wall of said casing being provided with a plurality of turned lips to form shoulders, a plurality of gripping-plates located in said casing, a standard passing through said plates and casing, means for holding said plates in engagement with said shoulders whereby said plates are held in position to grip said standard, one of said plates being provided with a projection passing through the wall of said 50 casing whereby said plate may be moved, and means for simultaneously releasing all of said plates from their gripping position by movement of the first-mentioned plate.

In testimony whereof I affix my signature 60 in presence of two witnesses.

CARL V. J. CHRISTENSEN.
